DESIGN FOR A LIGHTING FIXTURE

Edwin F. Guth, Webster Groves, Mo.

Application July 26, 1935, Serial No. 57,809

Term of patent 14 years

To all whom it may concern:

Be it known that I, Edwin F. Guth, a citizen of the United States residing at Webster Groves, in the county of St. Louis and State of Missouri, have invented a new, original, and ornamental Design for a Lighting Fixture, of which the following is a specification, reference being had to the accompanying drawing, forming part thereof, in which—

The figure is a side elevational view of a lighting fixture, showing my new design.

I claim:

The ornamental design for a lighting fixture as shown.

EDWIN F. GUTH.
